1-CARBETHOXYS-4-METHYLPIPERAZINE, ITS SALTS, AND METHOD OF PREPARING SAME

Hugh W. Stewart, Plainfield, N. J., assignor to American Cyanamid Company, New York, N. Y., a corporation of Maine

No Drawing. Application February 26, 1948, Serial No. 11,337

5 Claims. (Cl. 260—268)

1

This invention relates to new organic compounds and the methods of preparing the same. More particularly, the invention relates to 1-carbethoxy-4-methylpiperazine, its salts and methods of preparing said compounds.

In medical science there has long existed a need for compounds effective in the treatment of filariasis. In the past this disease has been treated with heavy metal organic compounds which, while being effective to some extent, must be used over a long period of time and have the relatively high toxicity characteristic of heavy metals in general. In a search for compounds effective in the treatment of filariasis, compounds of the type 1-carbethoxy-4-alkylpiperazine were prepared and tested. The compound 1-carbethoxy-4-ethylpiperazine is known, having been described in the literature by Moore et al., Journal of the Chemical Society, 39 (1929). This compound, when tested against filariasis in the cotton rat, proved to be only slightly active.

I have found, unexpectedly, that the compound 1-carbethoxy-4-methylpiperazine shows a high degree of effectiveness against filariasis. This activity is unusual because the activity of adjacent homologues such as 1-carbethoxy-4-ethylpiperazine shown in the reference above, was of a very low order.

The compounds of this general group may be illustrated by the following formula:

in which R is hydrogen or an alkyl radical. The relative activity of a number of these compounds is shown in the following table:

When R of the General formula is:	Minimum effective dose against microfilariae in the cotton rat
—H	25.0 (I. P.)
—CH ₃	6.25 (I. P.)
—C ₂ H ₅	50.0 (I. P.)
—n-C ₃ H ₇	25.0 (I. P.)
—iso-C ₃ H ₇	25.0 (I. P.)
—n-C ₄ H ₉	50.0 (I. P.)
—allyl	100.0 oral inactive
—n-heptyl	200.0 oral inactive

As shown in the above chart compounds such as 1-carbethoxypiperazine; 1-carbethoxy-4-n-propylpiperazine; 1-carbethoxy-4-isopropylpiperazine and 1-carbethoxy-4-n-butylpiperazine all show a low order of activity which is equal to or

slightly above that of the compound shown in the reference. The compound 1-carbethoxy-4-methylpiperazine is approximately eight times as effective as that of 1-carbethoxy-4-ethylpiperazine and at least four times more effective than any of the other compounds mentioned above. This high order of activity of the compounds of the present invention permits the obtaining of a therapeutic effect at a much lower dosage level, which in turn lessens the possibility of toxicity.

The new 1-carbethoxy-4-methylpiperazine may be prepared by reacting 1-carbethoxypiperazine or one of its salts with formaldehyde in a mineral acid such as hydrochloric acid and in the presence of zinc. The reaction is generally carried out in water or aqueous solutions of solvents such as dioxane, ethanol, and the like.

It is preferred that the reaction be carried out at a temperature below 50° C., preferably from about 0° to 25° C.

The preparation and description of the hydrochloride salt is given hereinafter. Other salts of 1-carbethoxy-4-methylpiperazine such as the hydrochloride, sulfate, dihydrogen citrate and the like, can be prepared in a similar manner.

To illustrate the invention with greater exactness the following description is given in which the new product is prepared from known intermediates. It will be understood, of course, that variations in the details may be made without departing from the initial features of the process.

To a solution of 106 parts of 1-carbethoxypiperazine hydrochloride in 200 parts of water is added 72 parts of zinc dust. With cooling and stirring, 63.5 parts of 36% aqueous formaldehyde is slowly added, keeping the temperature at 15° C. Then, while maintaining a temperature of 15° C. by cooling, slowly add with stirring 240 parts of 38% aqueous hydrochloric acid. The reaction is then stirred overnight at room temperature. The small amount of zinc present is removed by filtration and to the filtrate slowly add, while stirring and cooling, 50% aqueous sodium hydroxide solution at 20° C. until the first precipitate of zinc hydroxide re-dissolves, giving a turbid solution. The oil which separates is extracted with ether and dried over sodium sulfate. On distillation at 7 mm., the yield is 90 parts (96%) of 1-carbethoxy-4-methylpiperazine which distills at 96°—97° C. and is soluble in water.

By dissolving the 1-carbethoxy-4-methylpiperazine in absolute ethanol and passing in dry hydrogen chloride, 1-carbethoxy-4-methylpiper-

zine hydrochloride precipitates as a white solid. If desired, the hydrochloride salt may be recrystallized from ethanol. When pure, it melts at 168.5°-169° C.

I claim:

1. 1-carbethoxy-4-methylpiperazine, and salts thereof.
2. 1-carbethoxy-4-methylpiperazine.
3. 1-carbethoxy - 4 - methylpiperazine hydrochloride.
4. 1-carbethoxy-4-methylpiperazine dihydro-
gen citrate.

10

5. A method of preparing 1-carbethoxy-4-methylpiperazine which comprises mixing under reactive conditions a member of the group consisting of 1-carbethoxypiperazine and salts thereof with formaldehyde in the presence of a mineral acid and zinc.
